COMBINATION FISH SCALER, HOOK REMOVER, AND RULE

Ferdinand F. Salzmann, Box 5332,
Madison, Wis. 53705

Filed June 27, 1969, Ser. No. 17,933

Term of patent 14 years

Int. Cl. D22—08; D8—02
U.S. Cl. D22—31

FIG. 1

FIG. 2

FIG. 3

FIG. 4

FIG. 5

FIG. 6

FIG. 7

FIG. 1 is a top plan view of the combination fish scaler, hook remover, and rule embodying my new design;

FIG. 2 is a side elevation view of my new design;

FIG. 3 is an end elevation view from the left side of FIGS. 1 and 2;

FIG. 4 is an end elevation view from the right side of FIGS. 1 and 2;

FIG. 5 is a bottom view of my new design;

FIG. 6 is a top perspective view thereof; and

FIG. 7 is a bottom perspective view thereof.

I claim:

The ornamental design for a combination fish scaler, hook remover, and rule, as shown.
